UNITED STATES PATENT OFFICE.

ROBERT A. DRESSER, OF BRADFORD, PENNSYLVANIA.

PUMPING POWER FOR OIL WELLS.

Application filed August 21, 1925. Serial No. 51,721.

To all whom it may concern:

Be it known that I, ROBERT A. DRESSER, a citizen of the United States, residing at Bradford, in the county of McKean and State of Pennsylvania, have invented certain new and useful Improvements in Pumping Power for Oil Wells; and I do hereby declare the following to be a full, clear, and exact description of the invention, such as will enable others skilled in the art to which it appertains to make and use the same.

My invention consists in the novel features hereinafter described, reference being had to the accompanying drawings which illustrate one embodiment of the same, and a slight modification thereof, selected by me for purposes of illustration and the said invention is fully disclosed in the following description and claims.

The object of my invention is to provide a cheap and economical and convenient pumping mechanism for oil wells. As is well known, it is customary to drill a number of wells in an oil lease or property, and to arrange for the pumping of these wells from a power plant located adjacent thereto. These pumping installations usually include a power house covering the engine or motor for supplying the necessary power, and a separate building containing the pumping power mechanism, which is connected to the engine or motor, by a belt or otherwise, and is provided with horizontally rotatable cranks, or eccentrics, which are connected by means of a plurality of cables extending horizontally over the ground, and supported by pendulous supports from tripods or other supporting means, said cables extending to the various wells, at each end of which is located a bell crank, one arm of which is connected to one of the cables, the other arm to a vertical pump rod for the pump of that well. As the cranks or eccentrics are rotated, the several pumps connected therewith by the horizontal power cables, are actuated. It frequently becomes necessary to drive additional wells in the territory which is being pumped, contiguous to the power installation, and it very frequently happens that a well is sunk at such a location that it is impossible to run a pumping cable to the power mechanism on account of the power house, or some stationary part of the pumping power mechanism being in the way. This arrangement also necessitates the construction of two buildings, and adds

considerably to the cost of pumping the wells.

In order to secure a pumping power mechanism which can be connected with the wells in every possible direction, it has been proposed to place the actuating cranks, or eccentrics, at a considerable elevation above the ground and locate the engine or motor, and its operative connections for driving the cranks or eccentrics, below the same, but this is very objectionable for the reason that it is difficult to properly support the cranks or eccentrics, which are subjected to heavy lateral strains, so far above the foundations upon which the mechanism is supported, and secondly it makes it necessary to correspondingly elevate both the pumping cables and the means for supporting them at different points in their length, which is also objectionable and expensive.

According to my invention, I propose to provide a pumping power mechanism mounted upon a base plate supported upon a suitable foundation and provided with a pair of eccentrics located as close to the base plate or foundation as possible, and driven by a centrally located pinion, engaging a large gear wheel operatively connected with each of said eccentrics, eccentric rings engaging each of said eccentrics, and being provided with means for attaching the pumping cables at various points around their periphery, it being usually possible to have such cables extend in a straight line from each eccentric for more than 180° around each eccentric, without encountering any stationary part of the mechanism, and thus making it easily possible to extend pumping cables from one or the other eccentric of the power mechanism in every direction therefrom. This is permitted by the location of the motor for driving the power mechanism entirely above the plane of the eccentrics, together with all the necessary gearing between the motor and the eccentrics for driving the same. In order to provide a pumping power mechanism which can be constructed and sold at a low price, and which can at the same time be efficiently operated to drive the eccentrics at different speeds, I employ, preferably, an internal combustion engine of comparatively small power, which is connected to the pumping power mechanism by a train of gearing, so as to insure the operation of the eccentrics at the maximum speed when the

engine is running at normal speed. As is well known, an internal combustion engine develops its greatest efficiency when operating at high speed, and in this way I am able 5 to provide a comparatively inexpensive outfit. As it is often desired by persons purchasing a pumping power mechanism to drive the eccentrics at lower than their maximum speed, I may also provide suitable 10 change speed mechanism interposed, preferably between the motor and the train of gearing leading to the eccentrics, in order that the eccentrics may be driven at variable speeds according to the wishes of the owner, 15 without slowing down the speed of the motor, thus enabling the motor to operate at its most economic speed while the speed of the eccentrics may be changed by manipulating the change speed mechanism. 20 As before stated, I prefer to employ an internal combustion engine as the motor, and in such case, the motor, as well as the accessories, such as the fuel tank, radiator, etc., are all mounted above the eccentrics. In 25 some instances I may employ an electric motor in place of an internal combustion motor, which for the same reason is provided with change speed gearing and speed reducing gearing between the motor and the 30 eccentrics, so that the motor may run at its normal speed all the time, regardless of change of speed of the eccentrics, and obviating the use of anything more in the way of control mechanism for the motor than 35 the usual starting rheostat.

In many instances it becomes necessary to install a pumping power on a side hill where the surface of the ground slopes at a considerable angle, and in such case it is of course necessary that the plane of the eccentrics shall be substantially parallel to the surface of the ground as the pumping cables extend ordinarily a short distance above the ground and parallel thereto. As the tilting of the entire apparatus would have the effect of tilting the engine and interfering with the normal flow of lubricants and also the feed of liquid fuel and the circulation of water in the radiator, it is desirable in such instances to have the engine or motor in a vertical position, regardless of the inclination which it may be necessary to impart to the supporting base and the eccentrics. I therefore provide means whereby the engine may be rotated with respect to the engine shaft and the supporting means for the engine base, so as to maintain it in a truly vertical position regardless of the position of the base, and my invention also contemplates similar means for supporting an electric motor in case it is used for the source of power. My invention also comprises certain novel features of construction and combination of parts hereinafter fully described and particularly pointed out in the claims.

Referring to the accompanying drawings, Fig. 1 represents an end view of a pumping power mechanism embodying my invention.

Fig. 2 is a horizontal section on the line 70
2--2 of Fig. 1, the driving gears and pinion
for the eccentric being indicated in dotted
lines.

Fig. 3 represents a side elevation of the device showing it located upon an inclined supporting surface, the engine or motor being supported in vertical position. 75

Fig. 4 is a detail view, partly in section, showing a portion of the engine base and illustrating the means for supporting the same in different angular positions with respect to the main frame carrying the eccentric. 80

Fig 5 represents a detail view showing one of the supports for the engine or motor. 85

Fig. 6 represents a section on the line 6-6 of Fig. 4.

Fig. 7 represents a slight modification in which the engine is provided with change speed gearing.

Fig. 8 represents a further modification, in which the electric motor is substituted for the internal combustion engine illustrated in the preceding figures.

Fig. 9 represents a similar view to Fig. 8, showing a change speed gearing interposed between the motor and the train of gearing leading to the eccentrics.

Fig. 10 represents a detail sectional view 100 illustrating means for supporting the motor so that it can be maintained in vertical position, regardless of the position of the eccentrics.

In the embodiment of my invention illustrated in Figs. 1 to 6, inclusive, 1 represents the base plate of heavy cast iron intended to be supported by a suitable bed of cement, timbers, or otherwise on the field where the pumping power is to be utilized. Upon the base plate are mounted a pair of stationary, vertical, shafts, or pillars, indicated at 2—2, supported at their lower ends by the base plate and having their upper ends rigidly connected to a longitudinally disposed frame, 3, formed of girders or channel irons, suitably bolted or otherwise secured to the upper ends of the shafts or pillars, 2. The longitudinal frame, 3, preferably carries a transverse frame, indicated at 4, also composed of channel bars, bolted together and to the frame, 3, and to secure the greatest possible strength, I prefer to connect the outer ends of the transverse frame, 4, with the base plate by means of bracket arms, 5—5, bolted or otherwise secured thereto. This forms a very open, but extremely rigid and strong frame, in which the eccentrics and driving mechanism therefor, are supported, and upon which the motor for oper-

ating the eccentrics is superimposed. Each of the shafts, 2, is provided with an eccentric, 6, engaging an eccentric strap, 7, provided with a plurality of vertically disposed 5 pairs of apertures, indicated at 7^a, arranged in a circular series and adapted to receive vertical bolts, 8, by which the pumping cables may be attached to the eccentric rings. The eccentrics are mounted to rotate upon 10 the respective shafts or pillars, 2-2, and each eccentric is rigidly secured to a driving gear wheel, 9, preferably by means of bolts, indicated at 9^a. Between the large gear wheels, 9-9, is a small driving pinion, 15 10, on a vertical shaft, 11, supported in bearings in the base plate, 1, and in the longitudinal frame, 3, and extending between and through the transversely disposed frame, 4, where it is provided with a beveled gear 20 wheel, indicated at 12, which is engaged by a beveled pinion, 13, on a horizontal shaft, 14, mounted in suitable bearings on the transverse frame, 4. In order to prevent torsional strains on the transverse frame, 4, 25 its outer ends are connected with each end of the longitudinal frame, 3, by brace rods, 15-15. The shaft, 14, extends into a gear case, indicated at 16, and is provided within said case with a large gear wheel, 17, meshing 30 with a driving pinion, 18, on a shaft, 19, which is preferably coaxial with the driving or crank shaft of the motor, and is connected thereto by means of a clutch mechanism, indicated at 20, the specific construction 35 of which is unimportant and need not be particularly described.

21 represents an internal combustion engine, which is shown as mounted on the supporting frame work, entirely above and out 40 of the way of the pumping eccentrics. As it is frequently necessary to set up these pumping powers on a side hill, for example, I prefer to provide means for supporting the motor in a vertical position regardless of 45 the position which the base plate, 1, may occupy with respect to the horizontal. To this end I prefer to provide the inner end of the clutch case, 20, with a circular flange 22, and to provide the adjacent end of the 50 engine base with a similar circular flange, 23, one of these flanges, as the flange of the clutch case (see Fig. 6) being provided with a circular series of bolts apertures, 24, spaced very close together, and the flange 23, of the 55 engine case, in this instance, is provided with a plurality of bolt holes (six for example, as shown in Fig. 6) which may be brought into registration with certain bolt holes of the clutch case, 20, in a great variety of positions, so that the engine may be 60 rotated upon the longitudinal axis of its driving shaft with respect to the clutch case, 20, and secured in any desired position, by bolts, 25, engaging the registering apertures, 65 which will maintain the engine in a vertical 70 position, regardless of the position of the base plate and the base plate will be arranged on a side hill so that its inclination shall be in the direction of its greatest length, as shown in Fig. 3. In order to 75 enable the clutch case to support the weight of one end of the engine base and the parts mounted thereon, said clutch case is provided with a heavy bracket, indicated at 26, supported upon a portion of the transverse frame, 4. The other end of the engine base is preferably provided with means for supporting it in the desired position around the axis of its driving shaft, and in the present instance I have shown a supporting 80 bracket, 27, secured to the transverse frame, 4, and provided with a series of apertures, 28, arranged in a curve concentric with the axis of the engine shaft the latter being indicated at 29, and the adjacent end of the 85 engine base is provided with a pair of downwardly extending lugs, indicated at 30, having registering bolt apertures therein adapted to register with one or other of the apertures, 28, and to be connected with the bracket, 27, by a bolt, 31, thus rigidly supporting the engine base at both ends upon the frame work of the apparatus, to permit the engine to be adjusted in a rotary direction around the axis of its shaft, 29, in order 90 that it may be held in vertical position. Above the engine base I support a series of tanks for fuel, water, etc., so that all parts connected with the engine are located clear 95 of the eccentrics and their pumping cables or rods. For example, 32, is a tank for gasoline, for starting the engine, 33, is a tank for supplying heavier oil as kerosene for operating the engine, and 34, is a tank for supplying the radiator, 35, with water, and forming a part of the cooling system in a well known way. Any suitable internal combustion engine may be employed in connection with the device, and will be provided 100 with the usual means for starting and stopping it. The engine shaft can also be coupled to the shaft, 19, for driving the eccentrics by means of a clutch operating lever, 36, which in this instance is operated 105 by a cam, 37, mounted on the clutch case, 20, and operated by means of a lever, 38, and link, 39, within convenient reach of the operator. Referring to Fig. 2, it will be 110 seen that the pumping rods, or cables, indicated at 40, can be attached to the eccentrics, 6-6, in a very wide variety of positions extending considerably more than 180° around their respective axes, of rotation, so 115 that a pumping cable can be made to extend from one or the other of said eccentrics in practically every direction, and therefore no matter what additional wells may be connected to the pumping power, this can be accomplished without interference from any 120 part of the apparatus. It will also be seen 125

130

that a single house or enclosing structure can readily be placed around the entire apparatus to protect it from the weather, the pumping rods being permitted to reciprocate through suitable apertures provided for the purpose in the walls thereof.

In some instances it is desirable to operate the eccentrics at a different rate of speed, i. e., strokes per minute, from that which 10 may be preferred at another installation. It is also desirable to use the smallest power unit which will furnish the necessary power, and as an internal combustion engine develops its maximum power at a predetermined 15 speed of the engine shaft, it is in some instances desirable to provide change speed gearing between the engine shaft and the gearing leading to the eccentrics in order that the eccentrics can be driven at different 20 speeds in different installations, or under different circumstances, while the internal combustion engine is always operated at such a speed as to develop its maximum power. In Fig. 7, for example, I have shown 25 the engine, here indicated at 121, provided with a change speed gearing, indicated at 141, operated by a suitable shifting lever, 142, and interposed between the clutch mechanism, indicated at 120, and the pinion, 30 118, within the gear case, 116, which transmits the power to the eccentrics in the same manner as illustrated in the preceding figures. The engine is mounted in the same manner as previously described with reference 35 to Figs. 1 to 6, and the corresponding parts shown in Fig. 7 not specifically referred to, are given the same reference numerals with the addition of 100. In employing the construction illustrated in Fig. 40 7, it will be seen that by means of the change speed gearing, which may be of any usual or desired construction, the details of which form no part of my present invention, the engine itself may always be operated at its 45 most efficient speed, while the speed of the eccentrics may be varied, according to the desires of the operator.

In Fig. 8 I have shown the horizontal, transverse frame of the apparatus illustrated 50 in Fig. 1, which is designated at 204 in Fig. 8, provided with a superimposed electric motor, 243, connected with the clutch mechanism, indicated at 220, which is the same as that illustrated in the preceding 55 figures, and transmits the power of the motor to the driving pinion, 218, within the gear case, 216, in the manner hereinbefore described, the other corresponding parts of the apparatus being given the same numerals as in Figs. 1 to 6 with the addition 60 of 200. In order that the motor may occupy a vertical position, even though the device is installed on the side of a hill, I conveniently provide supporting mechanism 65 for the motor, illustrated in Fig. 10. In

this instance the horizontal frame, 4, is provided with a supporting saddle, indicated at 244, having its upper face provided with a concave portion, 245, curved concentrically with the axis of the motor shaft, 246. 70 The motor base is provided with a bracket portion, 247, having its lower face curved in the same curvature as the face, 245, of the saddle. It follows, therefore, that the motor may be rotated with respect to the saddle 75 around the axis of the shaft, 246, so that it will remain vertical, notwithstanding the fact that the lower portion of the apparatus is supported on the side of a hill, or other inclined supporting surface, thus keeping 80 the oil cups, oil passages, etc., truly vertical, and facilitating the lubrication of the device. The motor may be supported in its adjusted position by means of bolts, one of which is indicated at 248, engaging a nut, 85 249, rotatably mounted in the saddle, or other equivalent construction.

As an electric motor also operates most economically and with maximum efficiency at a predetermined speed of revolution of the armature, and as it is desirable to use as small a motor as possible in order to facilitate transporting the apparatus, which is usually employed in rather remote locations not easily accessible, I may, in some instances, provide, as indicated in Fig. 9, change speed gearing, indicated at 241, between the crank case, 220, and the driving gear, 218, so that the motor may always be operated at the same speed and without requiring anything further in the way of control mechanism than the ordinary starting rheostat.

In the operation of my improved pumping power, it will be understood that the engine or motor will be started in the usual manner and allowed to operate until its efficient speed has been obtained, when it will be connected by the clutch and the change speed mechanism, if that is employed, with the gearing leading to the eccentrics, thereby causing the eccentrics to rotate at the desired speed. The speed of the eccentrics may be varied to a certain extent, where an internal combustion engine is employed, by varying the position of the throttle valve, but for wide variations in speed of the eccentrics, I prefer to employ the change speed gearing, so that the speed of the motor will not be materially changed. 105 As the eccentrics are rotated, the eccentric straps, 7, will be caused to move, without rotating, in such manner as to impart a pull to each one of the pumping cables connected therewith. It will also be noted that as the 110 pumping cables extend in different directions with respect to the axis of the shafts, 2-2, the pull on each cable is to a certain extent counterbalanced by the weight of the pumping rod connected with a cable or 115 120 125 130

cables extending in a nearly opposite direction, so that an even and regular distribution of power is produced with corresponding ease and steadiness of operation.

5 What I claim and desire to secure by Letters Patent is:—

1. In a pumping power mechanism, the combination with an eccentric and an eccentric strap, provided with means for attaching pumping rods or cables thereto, a prime motor for driving the eccentric, mounted above the same, and gearing connecting the prime motor with the eccentric.

10 2. In a pumping power mechanism, the combination with an eccentric and an eccentric strap, provided with means for attaching pumping rods or cables thereto, a prime motor for driving the eccentric, mounted above the same, gearing connecting 15 the prime motor with the eccentric, and change speed mechanism interposed between the prime motor and said gearing for enabling the eccentric to be driven at varying speeds, without changing the speed of the 20 motor.

25 3. In a pumping power mechanism the combination with an eccentric and an eccentric strap, provided with means for attaching pumping rods or cables thereto, a prime motor for driving the eccentric, mounted above the same, reducing gearing 30 interposed between the motor and the eccentric, and change speed gearing interposed between the motor and said reducing gear- 35 ing.

40 4. In a pumping power mechanism, the combination with a base plate, provided with a pair of vertically disposed shafts, an eccentric mounted on each of said shafts adjacent to said base plate, a frame work supported by said base plate, and having a portion engaging the upper ends of said shafts, a driving shaft located centrally between said eccentric shafts and, gearing connecting 45 it with said eccentric shafts, a prime motor supported on said frame work above said eccentrics and gearing, and operatively connected with said gearing for driving said eccentrics, and eccentric straps engaging 50 said eccentrics and provided with means for connecting pumping rods or cables thereto, whereby said pumping rods or cables may extend in all directions from the pumping power.

55 5. In a pumping power, the combination with a base plate, a horizontal supporting frame located above the same and supported from the base plate, by supporting brackets connected to the base plate centrally between 60 its ends, a pair of vertically disposed stationary shafts mounted in the base plate and frame, eccentrics rotatably mounted on said shafts, gears connected with said eccentrics, a centrally located vertical shaft mounted in 65 said base plate and frame work, and pro-

vided with a driving pinion engaging said gears, a bevel gear carried by the upper end of said centrally located shaft, a horizontal driving shaft provided with a beveled pinion engaging said beveled gear, a prime 70 motor located above said frame work and supported thereby, gearing interposed between the shaft of the motor and said horizontal driving shaft, and eccentric straps, engaging said eccentrics and provided with 75 means for connecting pumping rods or cables thereto.

6. In a pumping power, the combination with a base plate, provided with a pair of vertically disposed stationary supporting 80 shafts, a supporting frame work secured to the upper end of said shafts, an eccentric mounted rotatably upon each of said shafts adjacent to the base plate, a prime motor mounted on the frame work and supported 85 entirely above the plane of the eccentrics, and driving connections from the prime motor to the eccentrics, eccentric straps engaging said eccentrics, and means for connecting pumping cables thereto. 90

7. In a pumping power, the combination with a base plate, and a supporting frame located above the same, rotatable eccentrics mounted between the base plate and the supporting frame, a prime motor mounted 95 above said supporting frame and supported thereby, bearing connecting the prime motor with the said eccentrics, eccentric straps for said eccentrics, and means for connecting pumping cables thereto, and means for adjusting the prime motor in a rotary direction with respect to the axis of its driving shaft to permit the motor to be supported 100 in vertical position when the base plate is located in an inclined position. 105

8. In a pumping power, the combination with a main frame, comprising a base and a super-structure supported therefrom, pumping eccentrics rotatably supported between the base plate and super-structure 110 and provided with eccentric straps having means for connecting therewith pumping cables, an internal combustion engine mounted upon and supported by the super-structure, reducing gearing for connecting 115 the shaft to said internal combustion engine with said eccentrics, and means for supporting said engine in different adjusted positions with respect to the axis of its driving shaft to permit said engine to be supported in a vertical position when the base and super-structure are in an inclined position. 120

9. In a pumping power, the combination with a main frame, comprising a base and a super-structure supported therefrom, pumping eccentrics rotatably supported between the base plate and super-structure and provided with eccentric straps having means for connecting therewith pumping cables, 125 130

- an internal combustion engine mounted upon and supported by the super-structure, and having its base provided at one end with a circular flange concentric with the axis of the driving shaft of the engine, a supporting casing secured to the super-structure and having a corresponding circular flange, said flanges being provided with registering bolt holes, whereby the engine base may be adjusted in a rotary direction with respect to the axis of its driving shaft, and secured to the supporting flange, the other end of the engine base being provided with means for supporting it from the frame work in any of its adjusted positions.
10. In a pumping power, the combination with a main frame, comprising a base and a super-structure supported therefrom, pumping eccentrics rotatably supported between the base plate and super-structure and provided with eccentric straps having means for connecting therewith pumping cables, an internal combustion engine mounted upon and supported by the super-structure, and having its base provided at one end with a circular flange concentric with the axis of the driving shaft of the engine, a supporting casing secured to the super-structure and having a corresponding circular flange, said flanges being provided with registering bolt holes, whereby the engine base may be adjusted in a rotary direction with respect to the axis of its driving shaft and secured to the supporting flange, the other end of the engine base being provided with a supporting part, said super-structure being provided with a bracket to engage said supporting part, said supporting part and said bracket being provided, the one with a plurality of bolt holes adapted to register with bolt holes in the other part, and a bolt for connecting said supporting part and bracket in any position to which the engine may be adjusted.
11. In a pumping power, the combination with a supporting frame comprising a base plate, vertically disposed stationary shafts secured thereto, a longitudinal frame secured to the upper ends of said shafts, and a transverse frame supported upon said longitudinal frame, pumping eccentrics rotatably mounted on said stationary shafts and provided with eccentric straps having means for engaging pumping cables, a gearing connected with each of said eccentrics, a vertical shaft rotatably mounted in said base plate and frames and provided with a pinion engaging both of said gears, and with a horizontal bevel gear, a horizontal shaft mounted on said transverse frame provided with a bevel pinion engaging said bevel gear, an internal combustion engine mounted upon and supported by said transverse frame and having its driving shaft operatively connected with said horizontal shaft.
12. In a pumping power, the combination with a supporting frame comprising a base plate, vertically disposed stationary shafts secured thereto, a longitudinal frame secured to the upper ends of said shafts, and a transverse frame supported upon said longitudinal frame, pumping eccentrics rotatably mounted on said stationary shafts and provided with eccentric straps having means for engaging pumping cables, a gearing connected with each of said eccentrics, a vertical shaft rotatably mounted in said base plate and frames and provided with a pinion engaging both of said gears, and with a horizontal bevel gear, a horizontal shaft mounted on said transverse frame provided with a bevel pinion engaging said bevel gear, an internal combustion engine mounted upon and supported by said transverse frame and having its driving shaft operatively connected with said horizontal shaft, means for adjusting said internal combustion engine in a rotary direction with respect to the axis of its driving shaft to maintain it in vertical position when the base plate is supported in an inclined position.

In testimony whereof I affix my signature.
ROBERT A. DRESSER.
